UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

MACHINE FOR FILLING BOXES.

1,360,438.

Specification of Letters Patent. Patented Nov. 30, 1920.

Application filed May 9, 1919. Serial No. 295,835.

To all whom it may concern:

Be it known that I, MICHAEL PARIDON, a citizen of the United States, and resident of Barberton, in the county of Summit and State of Ohio, have invented certain new and useful Improvements in Machines for Filling Boxes, of which the following is a specification.

This invention relates to box filling machines; having reference more particularly to machines for filling and closing boxes of the so-called tray-and-shuck type commonly used for containing matches; such, for example, as disclosed in Letters Patent of the United States No. 1,300,762 dated April 15, 1919.

Briefly described, the machine illustrated in said patent embodies a tray-and-shuck conveyer comprising an endless chain of links having lengthwise thereof two rows of spaced transverse walls; means arranged laterally of the horizontal path of the upper run of the conveyer for inserting box trays between the successive walls of one row; means arranged endwise of the conveyer for inserting box shucks between the successive walls of the other row; a trough-like hopper having a delivery throat for supplying matches to the progressing trays on the upper run of the conveyer, and traveling plunger mechanism for pushing the thus filled trays into their complementary shucks on the conveyer.

The object of my present invention is to improve the said patented machine in various particulars with the view of materially increasing the capacity and consequently the output of the machine, and also of insuring with greater expedition and certainty the quantitative measurement of the matches for delivery to the respective box trays.

To this end the invention, generally stated, comprises simple and efficient means whereby a plurality of box trays and their complementary shucks are simultaneously supplied to the conveyer; means whereby matches are delivered from a source of supply in accurately measured quantities simultaneously to a like plurality of trays, and means whereby the filled trays, when they are subsequently entered into the shucks during the travel of the conveyer, are rapidly ejected from the latter and transferred

to a suitable take-off mechanism; all as will be hereinafter fully described and claimed.

In the drawings—

Figure 1 is a side elevation of a box-filling machine embodying my invention.

Fig. 2 is a plan of the machine.

Fig. 3 is a transverse vertical section of the machine, as on the line 3—3 of Fig. 2.

Fig. 4 is a similar section, as on the line 4—4 of Fig. 2.

Fig. 5 is a sectional plan of the right-hand or receiving end of the machine, certain parts, including the match supply hopper, the respective chute structures for the trays and shucks, and the tray-and-shuck conveyer, being omitted for clearness.

Fig. 6 is a partial plan of the delivery end of the match hopper and a portion of the tray-and-shuck conveyer, showing the blades and adjuncts.

Fig. 7 is a similar section through the guide structure for the measuring blades, showing the slide bars for said blades, and the cam mechanism for operating the slide bars.

Fig. 8 is a longitudinal vertical section through the delivery end of the match hopper, and adjuncts, as on the line 8—8 of Fig. 6, illustrating measured quantities of matches in the respective throats preparatory to delivery to the underlying box trays on the tray-and-shuck conveyer.

Fig. 9 is a similar section through the throated portion of the hopper, showing the lower measuring blades of the respective throats as retracted and the matches delivered to the trays.

Figs. 10 and 11 are transverse vertical sections through the match hopper and the adjacent portion of the tray-and-shuck conveyer, as on the lines 10—10 and 11—11, respectively, of Fig. 8.

Fig. 12 is a perspective view of a twin plunger device, and adjuncts, for feeding spaced-apart box trays to the conveyer.

Fig. 13 is a skeleton perspective view of the measuring blades and the slide bars therefor.

Fig. 14 is a view of a fragment of the tray-and-shuck conveyer.

Fig. 15 is a plan of adjacent portions of the tray-and-shuck conveyer and of the plunger conveyer for nesting the trays and shucks, showing box-ejecting members in

section and also an inclined track structure for receiving the filled boxes ejected from the said conveyer.

Fig. 16 is a vertical section through the box-ejecting mechanism, showing a part of the tray-and-shuck conveyer, and adjuncts.

The main supporting frame of the machine illustrated in the drawings comprises a relatively long table 20; standards 21, and 10 a bed 22. The main power-driven shaft 23 extends longitudinally of and beneath the table and has its bearings in suitable boxes on the standards.

The tray-and-shuck conveyer 24 passes 15 about sprocket-wheels 25 mounted on transverse shafts 26 having their bearings in brackets 27 beneath the table near its respective ends. The upper run of this conveyer travels upon the top of the table and the 20 lower run is guided upon a longitudinal guide bar 28 supported by standards 29 rising from the bed 22. The shafts 26 bear pin wheels 30 which are engaged by adjacent cams 31 respectively on the main shaft 23, the peripheral grooves of said cams being of such contour as to impel the wheels 30 and perforce the conveyer intermittently 25 for a purpose as hereinafter mentioned.

In the present instance the conveyer comprises a succession of link members jointed together to form an endless chain, having 30 lengthwise thereof two rows of spaced transverse walls 32, 33 designed respectively to embrace and support the complementary 35 box trays and shucks in endwise relation to each other in such a manner that the trays can be slid lengthwise into their respective shucks.

Box trays (a) and shucks (b) therefore 40 are delivered to the links of the conveyer at the receiving portion of the latter, that is, at the right hand end of the machine as viewed in Figs. 1 and 2, in order that the complementary trays and shucks, supported 45 in endwise relation to each other as above mentioned, shall progress with the conveyer. The trays and shucks are respectively fed to the receiving spaces of the conveyer from opposite sides of the latter; the construction 50 and operation being such that two trays and two shucks are simultaneously positioned on the conveyer, and that the two spaces thus supplied are separated by a series of intervening spaces,—four in the present instance. 55 Each step movement of the conveyer is equal in extent to two adjacent spaces, that is, the length of a link, and the tray and shuck supply stations are so located that each alternate space is supplied with a tray and 60 shuck at the first station and each intervening empty space is supplied with a tray and shuck at the second station. Hence when the succeeding spaces of the conveyer pass the latter station they each contain a 65 tray and shuck.

The tray and shuck feeding mechanism includes two pairs of guide channels 34, 35 arranged on the table adjacent and at right angles to the respective sides of the conveyer. The channels 34 are designed to receive 70 empty trays and the channels 35 to receive the complementary shucks for said trays. Leading to each pair of channels is the lower end of an inclined chute structure 36 having two spaced apart parallel guide ways 75 77 down which the boxes, or shucks, arranged in endwise relation to each other, are progressively fed to the channels. Mounted to reciprocate in each pair of channels are two plungers 38 which are carried by slides 39 80 reciprocable in parallel guides in a bracket member 40 that is bolted to the table. (See Figs. 4 and 12). The plungers are guided in slotted basal extensions 41 of the chute structure, which extensions are snugly fitted 85 in the respective guide ways of the bracket member. Each of the slides is provided with a lug 42 which depends through a suitable slot 43 in the guide bracket and is connected by means of a link 44 with an arm 45 rising 90 from a rock-shaft 46 which has its bearings in brackets 47 extending from the side of the table. The outer ends of the two rock-shafts 46 are provided with inwardly 95 extending arms 48 having at their free ends rolls 49 in engagement with appropriate face cam grooves 50 formed in two corresponding gear-wheels 51, whereby during the concurrent rotation of said wheels the respective rock-shafts are actuated and the plungers simultaneously reciprocated within their respective channels 34, 35 in a direction toward and from the conveyer. One of the gear-wheels is fast on the main shaft 23, and the other wheel is fast on a shorter shaft 100 52 having its bearings in the main frame; an idler gear 53 on a stud-shaft 54 being interposed between and in mesh with the wheels 51. Thus the gear-wheels 51 are currently driven from the main shaft. 105

During the partial retraction of each pair of plungers 38 their inner portions lie directly below and extend inwardly beyond the lower ends of the guide ways 37 of the adjacent chute structure, and hence a pair 110 of box elements (trays or shucks) are delivered upon such portions of the plungers. When the plungers are fully retracted they escape such superposed elements and the latter drop upon the floors of the channels, 115 (34, 35) whereupon, in the succeeding inward stroke of the plungers, the opposing box elements are pushed along the channels and into the adjacent receiving spaces of the conveyer. 120

In order to insure the descent of the box elements within their respective channels, I preferably provide vertically movable pressure heads 55 which are adapted to bear upon and recede from such elements imme- 125 130

diately before the latter are pushed upon the conveyer. There are a pair of spaced pressure heads for each pair of channels, which heads are conveniently formed on the respective ends of a bar 56 which is secured to the up-standing limbs of a bifurcated plunger 57. In the present instance the extremities of the plunger limbs, which extend freely through perforated guide bosses on the table, are screw-threaded and provided with clamp nuts 59, whereby the bar is adjustably secured to the plunger. The lower end of this plunger is pivoted, as at 60, to one end of an arm 61 which is loosely hung on the adjacent rock-shaft 46. On one side of this arm is a roll 62 which engages the groove 63 of a face cam 64. There are two counterpart face cams 64, one for each set of pressure members, which cams are fast on the shafts 23, 52 respectively. The contour of the cams 64 is such that the arms 45 are correspondingly oscillated to effect the periodical raising and lowering of the pressure members for the purpose mentioned. (See Figs. 1, 2 and 4.)

The box trays supported on the conveyer are carried beneath a suitable match supply hopper by means of which quantities of matches are measured and delivered in alternation to two spaced-apart trays during each dwell of the conveyer while two trays and two shucks are being positioned on spaced rearward links of the conveyer. In the present instance a trough-like hopper is employed comprising an elongated inclined bottom 65 and sides 66, the space between which latter is slightly greater in width than the length of a match. The bottom is provided adjacent its lower end with two depending throat portions 67 arranged in spaced relation to each other correspondingly with each pair of tray and shuck channels 34, 35, and adapted to receive the matches and deliver them in measured quantities to the immediately underlying empty match trays on the conveyer. The hopper is longitudinally reciprocated in any usual or approved manner to effect the orderly descent of the matches from the upper or receiving end of the trough to its lower end, which latter end is constituted by a stationary end wall 88 supported by a bracket 88' rising from the table. This wall, during the longitudinal vibration of the body of the hopper, tends to direct the accumulated matches at the lower end of the hopper toward the throat portions. A rod 89, which is pivoted at its lower end to the bracket, overlies the inclined hopper throughout the greater part of the length of the latter, which rod, thus resting upon the contents of the hopper, serves as a top guard for the matches and also contributes to their descent during the vibration of the hopper.

The transverse walls of each throat portion of the hopper are slotted in different

horizontal planes, as at 68, 69 respectively, for the reception of a set of slide blades which are reciprocable across the throat at predetermined intervals. The set of blades comprises an upper pair 70 and a lower pair 71, which pairs are so spaced apart vertically that when they are positioned within and across the throat, as seen most clearly in Fig. 8, they provide between them a chamber substantially equal in capacity to the interior of a match tray. The slide blades for the respective throats are timely actuated and controlled to cut off and measure definite quantities of matches; that is to say, the lower blades are retracted, as seen in Fig. 9, to permit the discharge of the measured quantities of matches to the underlying empty trays while the upper blades remain in their inward or closing position; the lower blades are then positioned to close the lower portions of the throats and the upper blades are retracted to permit the descent of matches to and upon the lower blades; and the upper blades are then positioned to cut off the supply of matches and complete the measuring operation preparatory to the delivery of the matches to a succeeding pair of underlying trays as before; and so on.

In the present instance each blade is constituted by the right angular extension of a plate 72 which is affixed to a slide bar 73 mounted to reciprocate in a longitudinal guide structure 74 on the table 20. There are four slide bars arranged in superposed pairs, the upper pair carrying the respective upper plates of the two sets and the lower pair the respective lower plates. The series of bars are maintained in place by a suitable cap plate 75 on the guide structure. Each bar is provided on its outer edge with a pair of lugs 76 which project outwardly beyond the guide structure; the lugs of the respective bars being arranged in spaced relation to each other as shown. (See Figs. 1, 2, 6, 7 and 13). The lugs loosely receive the upper or knuckle ends of a series of rock-arms 77 which are arranged in two pairs carried by parallel rock-shafts 78 extending transversely of and beneath the table, and having their bearings in the latter. Depending from the shafts 78 are arms 79 equipped at their lower ends with rolls 80 which engage the respective grooves 81 of a barrel cam 82 fast on the main shaft 23, which grooves are arranged in oppositely related pairs respectively, as shown. (See Figs. 1 and 7). The grooves of one pair are adjacent to and parallel with each other in one half of their circumference, and gradually diverge and then converge throughout the remainder of the circumference; and the grooves of the other pair are widely separated from and parallel to each other in one half of their circumference and gradually converge and then diverge throughout

the remainder of their circumference. The parallel portions of one pair of grooves are in diametrically opposite relation to the parallel portions of the other pair; and hence when one pair of arms 79 are being oscillated by the working portions of one pair of grooves the other pair of arms are being held at rest by the parallel portions of the other pair of grooves; and the con- 10 verse.

One pair of arms 77 are connected with the lugs 76 of the respective lower bars 73, and the other pair are connected with the lugs of the respective upper bars. Hence 15 during each complete rotation of the cam 82 the two sets of measuring blades, as they may be termed, are operated in timely relation to each other, that is, in one half rotation of the cam the lower blades of each set 20 are maintained in their inward positions to partition the feed throats and provide temporary bottoms therefor, and in the remainder of the rotation said lower blades are retracted from the throats, as seen in 25 Fig. 9, and then returned to their inward positions preparatory to a succeeding dwell; the two pairs of upper blades being simultaneously operated reversely of the lower blades during such complete rotation; *i. e.*, 30 during the interval of rest (or closed position) of the lower blades the upper blades are gradually opened and then gradually closed preparatory to a succeeding dwell.

The hopper is provided with a suitably 35 disposed guide portion 83 which is slidably mounted on a guide post 84 rising from a cover plate 85 overhanging the conveyer, and the delivery end of the hopper is longitudinally extended, as at 86, and provided 40 with depending horizontal side flanges 87 which are prolonged laterally of the discharge throats of the hopper. These flanges are offset to receive and embrace the tray receiving portion of, and serve as a 45 guard and guide for the conveyer and trays in the region of the match filling station.

When the filled trays with their complementary shucks, are advanced beyond the hopper, such trays are successively pushed 50 into the shucks, preferably by means of an endless series of horizontally reciprocative plungers 90 mounted in spaced relation to each other on an endless conveyer 91, the upper run of which is arranged to travel 55 adjacent to, and in the same direction as, and concurrently with the upper run of the tray-and-shuck conveyer.

The plunger conveyer 91 herein illustrated comprises links jointed together in 60 endless series and supported by two sprocket-wheels 92, 93, the former of which is mounted on the left hand shaft 26, and the latter of which wheels is mounted on a shaft 94 having its bearings in brackets beneath the table. The shaft 94 is equipped with a pin 65

wheel 95 (similarly to the shafts 26) with the pins of which engages a cam 96 on the main shaft. Thus the plunger conveyer is timely driven in respect to the tray-and-shuck conveyer. The plungers, which are slidably 70 fitted in transverse guide ways in the links of the conveyer 91, are provided respectively with up-standing studs 97 adapted in the travel of the plungers, to enter an appropriate cam way 98 of an overhanging 75 plate structure 99 on the table, such studs thus being successively actuated to effect a gradual inward movement and then a corresponding return movement of the plungers in respect to the tray-and-shuck 80 conveyer. The forward or acting end of each plunger is provided with a thrust head 100 designed to act upon the opposing end of a filled tray in the conveyer 24, and push such tray directly into its complementary 85 shuck.

The guide bar 28 is usually constructed with an appropriate bearing portion 101 which underlies and supports the lower run of the plunger conveyer 91 in its travel. 90

A suitable hold-down device for the shucks is arranged in the region of their travel where the trays are successively entered into the shucks, which device comprises a block 102 carried by the free end of 95 a vertically movable arm 103 overhanging the path of the shucks. This arm being pivoted at its outer end to suitably disposed brackets 104 on the table, the block exerts sufficient holding pressure on the successive shucks passing thereunder at the time the trays are being entered into the proximate open ends of the shucks.

As the filled boxes, (*i. e.*, nested trays and shucks) approach the discharging (left-hand) end of the machine, such boxes are removed in succeeding pairs from the conveyer 24 by means of a suitable ejector and deposited upon an inclined track structure 105 on which they descend to an off-bearing 106. In the present instance the ejector comprises a pair of spaced fingers 107 which are formed on a sleeve fast on the inner end of a shaft 108 overhanging the discharge end of the machine, said sleeve having preferably a balance wheel or disk 107' formed thereon. The shaft 108, which has its bearing in a bracket 109 on the table, is provided at its outer end with a sprocket-wheel 110 connected by means of a chain 111 with a similar wheel 112 on the main shaft 23. Thus the shaft 108 and the ejector fingers are continuously rotated. The bracket 109 includes a suitable guard casing 113 for the rotating fingers. The shaft 108 125 is so timed and the fingers are so disposed in relation to the tray-and-shuck conveyer, that said fingers in a part of their rotation impinge against the inner ends of two adjacent boxes during each dwell of the con- 130

veyer, and thus sweep them endwise from the latter and upon the inclined track structure 105. (See Figs. 1, 2, 3, 15 and 16).

The track structure is supported by a bracket 114 on the adjacent end of the table 20; the upper surface of such structure being formed with a pair of spaced parallel guide channels 115 for the reception and guidance of the closed boxes. The off-bearing belt 106 is mounted to travel at right angles to and slightly below the lower ends of the channels 115 so that the boxes as they glide from the latter pass to and upon the belt. This belt is supported by a pair of spaced pulleys 116, (only one of which is shown) the shafts of which have their bearings in end projections of a table 117, one end of which is supported adjacent to the discharge end of the machine by columns 118. The table is preferably provided with a raised guide portion 119 which extends longitudinally of and supports the upper lead of the belt 106. The shaft of the pulley 116 adjacent the track structure is extended inward toward the main frame and is equipped with a pin wheel 120 with which engages a cam 121 on the main shaft, and hence an intermittent motion is transmitted to the off-bearing belt. The gearing just described is so timed that in each dwell of the off-bearing belt two pairs of boxes are discharged from the track structure, one pair thus being superposed on the other, as indicated in Fig. 3. As the off-bearing belt progresses the row of superposed filled boxes are carried to a suitable station for packing. An upstanding plate 122 affixed to and longitudinally of the table 117, adjacent the outer edge of the belt, serves as a guard rail for the boxes upon the latter.

It is to be understood that my invention is not limited to the exact details of construction herein disclosed, as the mechanism may be modified within the principle of the invention and the scope of the appended claims.

I claim—

1. In a box-filling machine, the combination of a conveyer having a succession of members adapted to receive and hold complementary trays and shucks in endwise relation to each other, means for intermittently advancing said conveyer, means leading to opposite sides of said conveyer for simultaneously supplying a plurality of trays and a like plurality of shucks to spaced-apart members of the conveyer, means for simultaneously supplying matches to a like plurality of spaced-apart trays on the conveyer, and means for thereafter nesting the filled trays and their complementary shucks.

2. In a box-filling machine, the combination of a conveyer having a succession of members adapted to receive and hold com-

plementary trays and shucks in endwise relation to each other, means for intermittently advancing said conveyer, a pair of spaced-apart tray guides leading toward one side of the conveyer, a pair of similarly spaced-apart shuck guides leading toward the opposite side of the conveyer, means for engaging the complementary trays and shucks delivered from the respective guides and simultaneously feeding them endwise of each other to and upon the conveyer, means for simultaneously supplying matches to each pair of spaced-apart trays on the conveyer, and means for thereafter nesting the succeeding filled trays and their complementary shucks.

3. In a box-filling machine, the combination of a conveyer having a succession of members adapted to receive and hold complementary trays and shucks in endwise relation to each other, means for intermittently advancing said conveyer, means for simultaneously supplying a plurality of complementary trays and shucks to said members, a hopper having two delivery throats in spaced relation to each other for simultaneously supplying matches to two spaced-apart trays on the conveyer, measuring devices for said throats, and means for nesting the filled trays and their complementary shucks.

4. In a box-filling machine, the combination of a conveyer having a succession of members adapted to receive and hold complementary trays and shucks in endwise relation to each other, means for intermittently advancing said conveyer, means for supplying complementary trays and shucks to said members, a hopper having two delivery throats in spaced relation to each other for simultaneously supplying matches to two spaced-apart trays on the conveyer, upper and lower measuring blades for each of said throats, operative connections between the upper blades of the respective throats, operative connections between the lower blades of said throats, and means for operating said upper and lower blade connections at predetermined intervals.

5. In a box-filling machine, the combination of a conveyer having a succession of members adapted to receive and hold complementary trays and shucks in endwise relation to each other, means for intermittently advancing said conveyer, means for supplying complementary trays and shucks to said members, a hopper having two delivery throats in spaced relation to each other for simultaneously supplying matches to two spaced-apart trays on the conveyer, a pair of upper measuring blades for each of said throats, a pair of lower measuring blades for each of said throats, a pair of slide bars to which the upper blades are connected, a pair of slide bars to which the lower blades are

connected, a cam element, and operative connections between said element and the respective slide bars.

6. In a box-filling machine, the combination with a conveyer having a succession of members for receiving and holding box trays, means for intermittently advancing said conveyer, means for simultaneously supplying a pair of box-trays to spaced-apart members, a hopper having two delivery throats in spaced relation to each other for simultaneously supplying matches to two spaced-apart trays on the conveyer, a pair of upper measuring blades for each of said throats, a pair of lower measuring blades for each of said throats, a pair of slide bars to which the upper blades are connected, a pair of slide bars to which the lower blades are connected, a cam element, and operative connections between said cam element and the respective slide bars.

7. In a box-filling machine, the combination with a conveyer having a succession of members for receiving and holding box elements, of a feed structure for said elements having its delivery end in spaced relation to one side of the conveyer, a horizontal plunger reciprocative beneath the delivery end of said structure and toward and from the conveyer, means for actuating said plunger, a pressure member vertically reciprocative in a plane intersecting the space between the said structure and the conveyer, and means for actuating said pressure member.

8. In a box-filling machine, the combination with a conveyer having a succession of members for receiving and holding box elements, of two feed structures leading toward but spaced from the respective sides of the conveyer, one of said structures being for box trays and the other structure being for box shucks, plungers reciprocative beneath the delivery ends of the respective structures, means for simultaneously actuating said plungers, pressure members vertically reciprocative in planes intersecting the spaces between the respective structures and the conveyer, and means for simultaneously actuating said pressure members.

9. In a box-filling machine, the combination with a conveyer having a succession of members for receiving and holding box elements, means for intermittently moving said carrier, and means for simultaneously feeding succeeding pairs of spaced-apart box trays to said members, of a hopper having two depending delivery throats overlying the path of the conveyer and spaced-apart correspondingly with each pair of trays.

10. In a box-filling machine, the combination of a conveyer having a succession of members adapted to receive and hold complementary trays and shucks in endwise relation to each other, means for intermittently advancing said conveyer, means for simultaneously supplying a plurality of complementary trays and shucks to spaced-apart members of the conveyer, means for simultaneously supplying matches to a like plurality of spaced-apart trays on the conveyer, means for nesting the succeeding filled trays and their complementary shucks, and means for simultaneously ejecting a like plurality of nested trays and shucks from the conveyer.

11. In a box-filling machine, the combination with a conveyer for a succession of closed boxes, of means for ejecting succeeding pairs of boxes from said conveyer, a downwardly inclined track structure to which the boxes are delivered, and an off-bearing belt to which the boxes are directed by said structure, said belt being on a lower level than the delivery end of the track structure and being adapted to receive superposed rows of boxes.

12. In a box-filling machine, the combination with a conveyer having a succession of members for carrying closed boxes, and means for intermittently actuating said conveyer, of means for ejecting succeeding pairs of boxes from the conveyer during its intervals of rest, said means comprising a pair of spaced fingers, a shaft therefor, and means for rotating said shaft.

Signed at Barberton, in the county of Summit and State of Ohio this 5 day of May A. D. 1919.

MICHAEL PARIDON.
